UNITED STATES PATENT OFFICE.

LAWRENCE W. DAUGHENBAUGH AND CLARENCE A. MARKLE, OF
CLEARFIELD, PENNSYLVANIA.

BRICK-PRESS BOX.

No. 849,214.

Specification of Letters Patent.

Patented April 2, 1907.

Application filed May 22, 1906. Serial No. 318,222.

To all whom it may concern:

Be it known that we, LAWRENCE W. DAUGHENBAUGH and CLARENCE A. MARKLE, citizens of the United States, residing at 5 Clearfield, in the county of Clearfield and State of Pennsylvania, have invented a new and useful Brick-Press Box, of which the following is a specification.

This invention relates to press-boxes for o the manufacture of pressed brick; and its principal object is to provide a box which may be readily repaired and adjusted at the brick yard or factory without the necessity of sending the whole of the box to a repair- 15 shop, as practiced at the present time.

A further object of the invention is to provide a press-box having detachable liners which may be readily placed in position without the exercise of any special mechanical 20 skill, the liners being readily interchangeable, so that when one set is worn another set may be readily substituted therefor.

A still further object of the invention is to provide a press-box and detachable liners of 25 such construction that there will be no danger of shearing or mutilating the securing bolts or screws during the operation of pressing the bricks.

A still further object of the invention is to 30 provide a novel form of pad or base member provided with detachable liners and facings of such construction as to permit ready renewal when worn, and, further, to provide a pad with a suitable face-plate or name-plate 35 which may be readily changed in accordance with the name to be stamped on the bricks.

With these and other objects in view, as will more fully hereinafter appear, the invention consists in certain novel features of construction and arrangement of parts, hereinafter fully described, illustrated in the accompanying drawings, and particularly pointed out in the appended claims, it being understood that various changes in the form, 40 proportions, size, and minor details of the structure may be made without departing from the spirit or sacrificing any of the advantages of the invention.

In the accompanying drawings, Figure 1 45 is a transverse sectional elevation of a press-box constructed in accordance with the invention. Fig. 2 is a detail perspective view of the various parts of the box, pad, and cover detached.

Similar numerals of reference are employed 55 to indicate corresponding parts throughout the several figures of the drawings.

The press-box 10 is formed of cast metal and may be of any desired size and shape for the formation of fire-brick, building-brick, or 60 any other class of bricks or blocks and may be of any size and of any desired shape. In the present instance the box 10 is rectangular in form and is provided with bolting-lugs 11, to be attached to the frame of the 65 press in the usual manner. The inner vertical walls of the box 10 are provided with horizontal grooves 15, which may be formed by milling-cutters or otherwise, and any desired number of grooves may be formed in 70 each of the walls, two of such grooves being shown in the present instance.

The liners 16 are formed of plates of any suitable material, preferably hardened steel, and these liners are provided with ribs 17 of 75 any desired shape or width, said ribs fitting snugly within the grooves, so that when the liners are subjected to downward pressure the strain will be taken up by the lower walls of the ribs and grooves. The ribbed portions 80 of the liners are provided with threaded openings 18, which terminate short of the inner faces of the liners and are designed to receive securing-screws 19, that extend through openings formed in the wall of the box, the 85 screws serving merely to draw the liners closely against the inner face of the box and maintain the same in proper position. During the action of the press, however, there is no shearing strain on these screws, this 90 strain being taken up by the ribs and grooves, as previously described.

The pad or lower plunger comprises a cast-metal plate 20, that is provided with a marginal recess extending around both its sides 95 and ends, and the upper face of the pan is milled or planed away at the opposite edges to form recesses 21, that are separated by a centrally-disposed longitudinal rib 22. On top of the rib 22 is seated the name-plate 24, which 100 may be held in place by suitable securing-screws formed in the pad, and where the main plates vary in thickness liners 26 may be employed to preserve the proper height.

The recesses 21 are arranged to receive 105 facing-strips 27, formed of any suitable material, preferably hardened steel, and these are tapped for the reception of securing-

screws 29, which, however, terminate short of the inner or upper faces of the strips. The marginal recesses of the pad serve to receive liner-strips 30 and 31, which are tapped into the body of the pad, the recesses being of greater depth than the heads of the securing-screws, so that there will be no danger of the latter engaging against the liners of the press-box proper. The strips 30 and 31 become worn by contact with the vertical liners and may be readily detached and new ones substituted when occasion requires. The cover 34 is provided with longitudinal grooves 35 for the reception of a rib 36 of a liner 37, which is preferably formed of the same material as the remaining liner, and this liner is held in place by suitable securing-screws 38. The construction is such that every part of the box which engages with the material to be pressed into bricks is detachable, and the detachable connections are of such construction as to permit the removal of any of said liners and the substitution of new liners without the exercise of any special mechanical skill, thus avoiding the necessity of sending the entire press-box to the repair-shop, as now practiced.

We claim—

1. In a brick-press, a press-box, detachable liners therefor, and means for securing the liners in place, the press-box and liners having closely-interfitting connections to prevent shearing strain on the securing means.
2. In a brick-press, a press-box, detachable liners therefor, the box and liners having

closely-interfitting ribbed and grooved connections, and screws extending through the walls of the press-box into the ribbed portions of the liners, shearing strain on the screws being prevented by the ribbed and grooved connections.

3. In a brick-press, a press-box, detachable liners therefor, the box being provided with horizontal grooves, liners having ribs closely fitting within said grooves, and screws extending through the walls of the press-box into the ribs of the liners, shearing strain on said screws being prevented by the ribbed and grooved connections.

4. In a brick-press, a press-box having horizontally-disposed grooves at its inner walls, liners having horizontal ribs fitting within said grooves, securing-screws extending through the vertical walls of the press-box and tapped into the ribbed portions of the liners.

5. In a brick-press, a pad comprising a plate having a recessed upper face and provided with a continuous marginal recess, a detachable name-plate carried by the pad, facing-strips arranged in the recessed upper face of the pad, and liner-strips secured within the marginal recesses of said pad.

In testimony that we claim the foregoing as our own we have hereto affixed our signatures in the presence of two witnesses.

LAWRENCE W. DAUGHENBAUGH.
CLARENCE A. MARKLE.
